Specification of Letters Patent.

Patented July 6, 1915.

Application filed August 9, 1912. Serial No. 714,149.

To all whom it may concern:

Be it known that I, JOHN H. TIMBRELL, a citizen of the United States, residing at Broadway, in the county of Warren and 5 State of New Jersey, have invented certain new and useful Improvements in Flying-Machines; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification. 15

This invention relates, generally, to improvements in flying machines or aeroplanes; and, the present invention has reference, more particularly, to improvements 20 in that class of flying machines provided with a gyro-plane.

The present invention has for its principal object to provide a flying machine or aeroplane of the general character and construction hereinafter more fully set forth, 25 with a device known as a gyroplane, and means for operating the same, either by motor-power or by hand, so that in case of accident to the motor, the gyroplane may 30 be kept in revolution by means of hand-power, thus enabling the operator to allow the machine to gradually settle to the earth without danger to the machine or to the occupants.

35 A further object of the present invention is to provide a novel and simply constructed mechanism by means of which the propeller may be disconnected from the motor allowing the gyro-plane only to be operated, and 40 thus enabling the operator to raise the machine directly from the ground without first gaining sufficient momentum by the use of wheels and the exerted motor-power for driving the same, and when the flying machine has risen to any desired height the 45 propeller may be engaged in connection with the gyro-plane.

A further object of the invention is to provide in connection with a flying machine, a gyro-plane which when the machine

is in motion, maintains the stability of the machine to prevent the flying machine turning "turtle" when struck by sudden gusts of wind.

The invention has for its further object to 55 provide a series of operated blades in the gyro-plane which enable the operator to lower or raise the machine without the use of the raising or lowering planes situated at the extremities of the machine; and furthermore, the blades may be set at any desired angle, when the machine is in forward motion, to offset the lifting power of the gyro-plane and enable the operator to maintain his desired height. 60

Other objects of this invention not at this time more particularly enumerated will be clearly understood from the following detailed description of the present invention. 65

With the various objects of the present 70 invention in view, the invention consists, primarily, in the novel flying machine or aeroplane provided with a gyro-plane hereinafter set forth; and, the invention consists, furthermore, in the various arrangements and combinations of the several devices and parts, all of which will be more 75 fully described in detail in the following specification, and then finally embodied in the clauses of the claims which are appended to and which form an essential part of this specification. 80

The invention is clearly illustrated in the accompanying drawings, in which:—

Figure 1 is a top or plan view of a flying 85 machine or aeroplane provided with a gyro-plane, all made according to the principles of the present invention, and illustrating one embodiment of the principal features of this invention; Fig. 2 is a side elevation 90 of the same, the steering rudder and its operating mechanism, however, being omitted from said view; and Fig. 3 is a front view of the flying machine. Fig. 4 is a detail horizontal sectional representation, on an 95 enlarged scale, of portions of the flying machine, said section being taken on line 2—2 in said Fig. 2, looking in the direction of the arrow α . Fig. 5 is a detail view, partly in elevation and partly in vertical section, 100

of the gyro-plane and its vertical shaft, showing in connection therewith mechanism for driving the shaft by hand-power, a slideable gear on said shaft and a foot-treadle 5 connected therewith for disconnecting said gear from the motor-driven mechanism, and means for variously and angularly setting the adjustable blades of the gyro-plane; and Fig. 6 is a detail elevation of the 10 blade-setting means connected with the gyro-plane.

Similar characters of reference are employed in all of the above described views, to indicate corresponding parts.

15 Referring now to the several figures of the drawings, the reference-character 1 indicates a complete flying machine or aeroplane embodying the principles of the present invention, the same in the present instance comprising a main frame-work, as 2, 20 see Fig. 1 of the drawings, the said frame-work having any suitable marginal configuration.

The reference-character 3 indicates a ring-shaped member, forming a part of the said 25 main frame-work, and which is tied to the main frame-work 2 by means of suitably disposed tie-rods or bars 4 and 5. Connecting the two laterally extending tie-rods 4 30 with the main frame-work 2 are other suitable tie or strengthening rods 6. Suitably connected with the rear portion of the said main frame-work 2 is a ring-like member or element 7, a suitable tie-rod 8 extending 35 across this ring-like member or element 7 and longitudinally of the body of the flying-machine, said rod 8 being also suitably connected with the ring-shaped member 3. A cross or strengthening rod or bar 9 may also 40 connect portions of the said ring-like member or element 7 with the said longitudinally extending tie-rod 8.

Suitably hinged to or pivotally connected with the forward portion of the main frame-work 2 is a frame 10, and similarly connected with the rear portion of that part of the main frame-work formed by the ring-like member or element 7 is another frame 11.

50 The various frame-portions of the flying machine are covered with suitable sail-cloth, canvas, or the like, so as to provide the main plane 12 having an open part 13 which is formed by the said ring-shaped member 3, 55 and in which the gyro-plane, previously mentioned, is rotatably arranged in the manner to be hereinafter more fully explained. The hinged or pivoted frames 10 and 11 are also covered with sail-cloth or canvas, as 14. 60 Extending downwardly from the said main frame-work 2, and disposed at suitable intervals, are suspension rods, as 15 and 16, the rods 15 being connected by two sets of tie-rods, as 17 and 18, and the rods 16 being 65 connected with some of said rods 15, as

shown more particularly in Fig. 2 of the drawings, by tie-rods 19. Connected with the rods 17 and others of said rods 15 is a suitable frame-work 20 providing a suitable support for a motor 21 from which extends 70 longitudinally of the flying machine and rearwardly, the main driving shaft 22, and a propeller-shaft 22', upon which is suitably mounted a propeller 23.

The reference-character 24 indicates other 75 tie-rods or horizontal supports which carry a suitable platform, as 25. Extending above the said platform, as shown in the several figures of the drawings, is an arrangement of vertical rods or posts 26, the 80 said rods or posts also extending through and beneath the said platform and having their free extremities suitably connected with the tie-rods 27 and 28 of the lower frame-work of the flying machine, as indicated in the dotted outline in Fig. 4.

As shown in Fig. 2, the front and rear rods or posts 26 are made with suitably bent portions 29 which provide suitable bearings in alignment with and in which the previously-mentioned motor shaft 22 and the propeller-shaft 22' respectively revolve, as will be clearly evident. The said vertical rods or posts 26 are provided upon their upper extremities with suitably formed 95 bracket-like members or elements, as 30, formed with bearing-portions or ears each pair of which carries a pin 31, and rotatably arranged upon each pin 31 is a roller 32. Suitably connected with the said front and 100 rearwardly placed vertical rods or posts 26 is a frame-piece or arms 33 having a bearing 34 in which is rotatably mounted a vertical shaft 35 carrying upon its upper end portion a gyro-plane of the general construction and for the purposes to be presently more fully described. Upon its lower end portion, the said shaft 35 is provided with a spline 35' upon which is slidably arranged, and is adapted to rotate with said shaft, a 110 bevel-gear 36 and its hub 37. The said gear is preferably arranged beneath the platform 25, and its hub 37 extends into and through an opening 38 in said platform. The shaft 35 is held in its rotatable relation, against 115 vertical sliding movement in the bearing 34, by an arrangement of collars 39 and 40 which are fixed to said shaft, as shown in Fig. 5. The said bevel-gear 36 and its hub 37 are held against displacement from the 120 lower end-portion of the shaft 35 by a nut 41 which is screwed upon the end of said shaft, or by means of other suitably formed retaining or holding means, as will be clearly evident.

In order to slide the said bevel-gear 36 and its hub 37 in an upward direction from its normal initial position, indicated in said Fig. 5, the said hub is made with an annular groove 42 in which is arranged the forked end 44 of a foot-lever or 125 130

treadle 43 which is pivoted, as at 45, in a suitable bearing-bracket 46 mounted upon the platform 25, and the operation of which will be clearly understood from an inspection of said Fig. 5. Under normal initial conditions, the said bevel-gear 36 is in mesh with a bevel-gear 47 which is mounted upon the previously-mentioned motor shaft 22. Thus it will be seen, that the rotary motion 10 of the said motor-shaft 22 is transmitted directly to the said gyro-shaft 35, but the latter can be disconnected from the motor-shaft when the bevel-gear 36 is moved out of engagement with the bevel-gear 47, by 15 actuating the foot-lever or treadle 43. To convey the rotary motion of the motor-shaft 22 to the propeller shaft 22', the said shaft 22' is provided with a spline 51 upon which is slidably arranged a bevel-gear 49 and its 20 hub 50, said hub being also provided with an annular groove 48, or the equivalent thereof, pivotally mounted in a bearing-portion or bracket, as 52, upon the platform 25, is a hand-lever 53, extending through said platform, and having a forked end, as 54, in 25 operative engagement with the grooved part of the hub 50 for throwing the bevel-gear 49 into or out of mesh with the bevel-gear 36. When the gear 49 is in mesh with the gear 36, the rotary motion of the motor-shaft 22 will be communicated to the propeller-shaft 22', to actuate the propeller 23, as will be clearly evident.

When it is desired to rotate the vertical 30 gyro-shaft 35 from the motor shaft 22, without driving or actuating the propeller shaft 22' and the propeller 23, all that is necessary is to operate the hand-lever 53 in such a manner that the gear 49 will be thrown out 35 of mesh with the gear 36, whereupon the shaft 22 and its bevel-gear 47 will merely cause the gyro-shaft to be revolved, as will be clearly evident. If, however, it is intended to revolve the said gyro-shaft 35 and 40 its gyro-plane by hand, in case of an accident to the motor, while up in the air, or for other reasons, the bevel-gear 36 is lifted out of mesh with the bevel-gear 47 by actuating the foot-lever or treadle 43, and the 45 shaft 35 is caused to revolve by means of a manually operated mechanism. One form of such manually operated mechanism consists, essentially, of a pair of bearing-collars 55 and 56 suitably affixed to the rear vertical 50 rod or post 26, heretofore-mentioned, by means of pins or set-screws 57, said collars 55 and 56 being connected by a bracket-like bar or member 58 which is formed with a bearing 59. Rotatably mounted upon that 55 part of the said rod or post 26 located between the said collars 55 and 56 is a bevel-gear 60 which has a hub 61 formed or provided with a sprocket-wheel 62. Suitably mounted upon the gyro-shaft 35 is a 60 sprocket-wheel 63, and 64 indicates a link-

chain which passes over the said sprocket-wheels 62 and 63, and by means of which the rotary motion of the shaft 35 is produced.

Rotary motion of the bevel-gear 60 and the sprocket-wheel 62 is accomplished by 70 means of a bevel-gear 65 mounted upon a spindle 66 which is rotatably arranged in the bearing 59, said spindle 66 having affixed thereto a collar 67 which is provided with receiving notches 68, and with which can 75 be brought into operative engagement, by the operator, the lugs 69 of a crank 70 which is loosely mounted upon said spindle 66. To prevent accidental displacement of the crank from said spindle, the latter is provided upon its free end-portion with a nut 71, or other suitable enlargement. The operation of these parts is very simple and will be clearly understood from an inspection of Fig. 5 of the drawings. While the 80 mechanism shown in said Fig. 5 is represented as one means for manually operating the shaft 35, it will be understood that any other means may be used for accomplishing the same purpose.

The gyro-plane herein-above mentioned consists, essentially, of a large ring-like element 72 of a suitable light material, and which may be composed of laminated ring-like members, as indicated at 73, and which 90 may serve as collectors of the electricity contained in the air and produced by the frictional rotation of the rapidly moving ring-like element 72 through the air, the 95 electricity produced and collected being suitably diverted into and transmitted by electrical instrumentalities to storage batteries, or other electrical devices, with which the flying machine may be provided, but which, however, are not shown in the accompanying 100 drawings, as I propose to make separate application for Letters-Patent therefor. The arrangement of the said ring-like element 72 with relation to the main plane 12 is such that the said element may be located 105 directly in the open space 13, concentric with the ring-shaped member 3. To produce the relative arrangement of the said parts, I have provided a ring-like disk, as 74, which rests upon the previously-mentioned 110 rollers 32, and rotates thereon, the said disk 74 being provided with an arrangement of upwardly extending posts, as 75, with which 115 are suitably connected an upper ring 76, and a lower ring 77. Connected in a suitable 120 manner with said upper ring 76 and the ring-like element 72 are suitable stiffening spokes 78, preferably steel rods; and, similarly connected with the lower ring 77 and said ring-like element 72 are other suitable 125 stiffening spokes 79, also preferably in the form of steel rods. Suitably connected with the several spokes, and with the said rings 76 and 77 and the said ring-like element 72, are a number of supporting vanes

or wings, as 80, which are made of sail-cloth, canvas, or other suitable material, suitable open spaces, as 81, being left between some of said vanes or wings 80, for the purpose 5 to be presently more fully specified. Suitably connected with and arranged between the said upwardly extending posts 75 is a canopy-like retaining or holding member 82, which is made with a suitable hub, as 83, 10 into and through which the upper end-portion of the gyro-shaft 35 extends, and to which said hub is suitably and permanently affixed, so that the gyro-plane produced by the ring-like element 72 and the wings or 15 vanes 80, and their connecting parts, will rotate with the rotary movement of the gyro-shaft 35. As shown, the said ring-like element 72 is provided with bearing- 20 portions or receiving sockets 84, and the said canopy-like retaining or holding member 82 is also provided with bearing-portions 85, said bearing-portions 84 and 85 being in central alinement with the said open spaces 81. Oscillatorily arranged in the said bearing-portions 84 and 85 are the respective 25 end-portions of suitable rods or bars 86, each rod extending across an open space 81 and having fixed thereon, so as to be movable with the rod or bar 86, a deflector-vane 30 or blade 87.

The upper portion of the shaft 35 is made with a groove 88 in which is secured a spline or key 89, and slidably arranged upon said portion of the shaft 35, and the 35 key 89 thereon, is a sleeve 90. This sleeve is provided with a number of upwardly projecting fingers, as 91, and the said fingers 91 are pivotally connected by means of pins 92, see Fig. 6, with the slotted portions of 40 short arms 93 which are connected with the end-portions of the respective deflector-vane or blade-carrying rods or bars 86. Thus, it will be seen, that by moving the 45 said sleeve 90 in either an upward or a downward direction, the rods or bars 86 are oscillated and the deflector-vanes or blades suitably set at such angles to the plane of the gyro-plane, as may be necessary, while moving the flying machine upwardly or downwardly through the air, or 50 while floating horizontally. That the said sleeve may be moved in its upward or downward direction upon the shaft 35, the said sleeve is provided with an annular 55 groove 94 in which is a ring or sleeve 95 provided with pins 96. Operatively connected with said pins 96 is the forked end-portion 98 of a lever 97, said lever being pivotally connected, as at 99, to one of said 60 rods or posts 26, substantially as shown in Fig. 6 of the drawings, and being provided with a handle 100 which is suitably connected with said lever 97, to properly operate the said parts.

65 To operate and set the previously-men-

tioned frames 10 and 11, forming the vanes 14 at the front and rear of the flying machine, any suitable means under the control of the operator may be employed. One means is to provide the respective frames 70 10 and 11 with downwardly projecting arms 101 and 102, the arm 101 having a slotted end-portion 103 and the arm 102 having a slotted end-portion 104. Pivotally connected by means of pins or bolts 105 and 106 to the 75 slotted end-portions of the respective arms 101 and 102 is a rod 107 which is provided with a grasping lever or handle 108, for moving said connecting rod 107 in a forward or rearward direction, to angularly set the two 80 vanes 14, as will be clearly evident.

Having in the foregoing description set forth in a general manner one arrangement and combination of devices and parts comprising the principles of the present invention, I will now briefly set forth the manner of raising and lowering the flying machine, and at the same time maintaining its stability while sailing at any height in the air, irrespective of any conflicting air-currents.

In starting, the motor is set in operation, the propeller-shaft and its propeller having been thrown out of gear, so that the propeller will be out of action, the shaft upon 95 which the gyro-plane is mounted being in gear with the motor-driven shaft. The result is that the gyro-plane lifts the flying machine from the earth into the air, without the use of the usual running wheels ordinarily employed. Upon reaching the height desired, the propeller-shaft and propeller are also thrown into gear, whereby the flying machine is propelled through the air, in the manner usual in flying machines, 100 the vanes 14 being used for raising and lowering the flying machine during its flying operations. During these operations, the gyro-plane is still in motion, and during 105 the propulsion of the flying machine will maintain its stability irrespective of conflicting air-currents which would otherwise tend to cause the flying machine to turn "turtle." At the same time, the blades in the gyro-plane may be operated to lower 110 or raise the flying machine without the use of the raising and lowering vanes located at the extremities of the flying machine.

In case of accident to the motor or propeller, whereby the flying machine would 115 be rendered uncontrollable, and which might cause its destruction and endanger the life of the operator, the gyro-shaft can be thrown out of gear with the motor-shaft, the gyro-shaft being manually operated, 120 and at such speed, that the gyro-plane will counteract the falling speed of the flying machine, so that the gyro-plane acts very much like a parachute, and allows the flying machine to be easily and slowly lowered 125 130

without any danger to life or destruction of the flying machine. The lowering speed may also be regulated by angularly setting the blades contained in the gyro-plane, for 5 maintaining a fast or slow lowering speed.

Of course, I am aware that changes may be made in the general arrangements and combinations of the various devices and parts, as well as in the details of the construction of the said parts and the frame-work of the machine, without departing from the scope of the present invention as set forth in the foregoing specification and as claimed in the clauses of the claims which 10 are appended thereto. Hence, I do not limit my present invention to the exact arrangements and combinations of the various devices and parts, as described in the said specification, nor do I confine myself to 15 the exact details of the construction of the said parts and the frame-work of the machine, as illustrated in the accompanying drawings.

I claim:

25 1. A flying machine comprising in combination with the main frame-work thereof, a main plane mounted upon said frame-work, a shaft vertically mounted upon said frame-work, means for actuating said shaft, vertical 30 posts connected with said frame-work, roller-bearings upon said posts, a ring-like disk rotatably arranged upon said roller-bearings, upwardly extending posts upon said ring-like disk, rings connected with said last-mentioned posts, a canopy-like holding member upon said shaft, said member being secured to said last-mentioned posts, and a gyro-plane connected with said rings.

2. In a flying machine, the combination 40 with the frame-work thereof, of a main plane mounted upon said frame-work, a shaft vertically mounted upon said frame-work, means for actuating said shaft, vertical posts connected with said frame-work, 45 roller-bearings upon said posts, a ring-like disk rotatably arranged upon said roller-bearings, upwardly extending posts upon said ring-like disk, rings connected with said last-mentioned posts, a canopy-like holding member upon said shaft, said member being secured also to said last-mentioned posts, and a gyroplane connected with said rings, said gyro-plane consisting of a ring-like element, stiffening spokes between said 50 rings and said ring-like element, and supporting vanes connected with said spokes, said rings and said ring-like element, said supporting vanes being provided with openings between some of them, blades upon said rods, and means for angularly setting said blades, consisting of a sleeve slidably mounted upon said shaft, upwardly extending fingers upon said sleeve, and crank-arms between said fingers and the rods upon which said blades are arranged.

with the frame-work thereof, of a main plane mounted upon said frame-work, a 60 shaft vertically mounted upon said frame-work, means for actuating said shaft, vertical posts connected with said frame-work, roller-bearings upon said posts, a ring-like disk rotatably arranged upon said roller-bearings, upwardly extending posts upon 65 said ring-like disk, rings connected with said last-mentioned posts, a canopy-like holding member upon said shaft, said member being secured also to said last-mentioned posts, a gyro-plane connected with said rings, said gyro-plane consisting of a ring-like element, stiffening spokes between said rings and said ring-like element, and supporting vanes connected with said spokes, 70 said rings and said ring-like element, said supporting vanes being provided with openings between some of them, blades in said openings, and means for angularly setting said blades.

4. In a flying machine, the combination 80 with the frame-work thereof, of a main plane mounted upon said frame-work, a shaft vertically mounted upon said frame-work, means for actuating said shaft, vertical 85 posts connected with said frame-work, roller-bearings upon said posts, a ring-like disk rotatably arranged upon said roller-bearings, upwardly extending posts upon said ring-like disk, rings connected with 90 said last-mentioned posts, a canopy-like holding member upon said shaft, said member being secured also to said last-mentioned posts, a gyro-plane connected with said rings, said gyro-plane consisting of a ring-like element, stiffening spokes between said rings and said ring-like element, and supporting vanes connected with said spokes, 95 said rings and said ring-like element, said supporting vanes being provided with openings between some of them, oscillatory rods arranged in said openings, blades upon said rods, and means for angularly setting said blades, consisting of a sleeve slidably mounted upon said shaft, upwardly extending fingers upon said sleeve, and crank-arms between said fingers and the rods upon which said blades are arranged.

In testimony, that I claim the invention set forth above I have hereunto set my hand 110 this 6th day of August, 1912.

JOHN H. TIMBRELL.
